UNITED STATES PATENT OFFICE.

MURRAY C. DAMON, OF LEOMINSTER, MASSACHUSETTS.

DESIGN FOR A BUTTON.

57,825.

Specification for Design.

Patented May 10, 1921.

Application filed October 8, 1920. Serial No. 415,706. Term of patent 3½ years.

To all whom it may concern:

Be it known that I, MURRAY C. DAMON, a citizen of the United States, and a resident of the city of Leominster, county of Worcester, State of Massachusetts, have invented a new, original, and ornamental Design for Buttons, of which the following is a specification.

My design is represented in the accompanying drawing in which:

Figure 1 is a plan view of a button showing my new design.

Fig. 2 is a section on line 2—2 of Fig. 1.

Fig. 3 is a section on line 3—3 of Fig. 1.

The shape of the button is that of a convex polygon. The lower surface is substantially flat and the upper surface is provided with a raised portion of substantially diamond shape, the sides, however, extending between the extremities of the major axis thereof being curved. The raised central portion, as aforesaid, is situated diagonally of the button and extends from the lower corner at one side of the button to the upper

corner at the other side thereof. The sides or walls of the raised portion are beveled, flaring from the top outwardly and downwardly, and the upper surfaces of the portion of the button extending toward the central raised portion slope so as to form substantial grooves where they meet the lower edges of the beveled sides of the centrally arranged diamond shaped raised portion.

The button may be colored in any suitable manner.

The eyelet structure for the securing threads is a purely mechanical feature and forms no part of my design.

I claim:

The ornamental design for a button substantially as shown and described.

In witness whereof I have hereunto set my hand at Leominster, county of Worcester, State of Massachusetts, this 2nd day of October, 1920.

MURRAY C. DAMON.
